NEW YORK.

AUTOMATIC PRESSURE LATCH.

Application filed June 11, 1926. Serial No. 115,174.

This invention relates to automatic pressure latches and has for its object to provide a device of the class specified, simple in construction and adjustment and efficient in operation.

To these ends and others which will appear later herein, our improvements comprise features illustrated in their preferred embodiment in the drawings accompanying this specification, wherein:

Figure 1 is a rear elevation of a latch mechanism to which our improvements are applied. Fig. 2 is a side elevation corresponding with Fig. 1. Figs. 3 and 4 are elevations similar to that of Fig. 2 showing steps in the operation of the mechanism. Fig. 5 is a side elevation of a detail corresponding with Fig. 2 and Fig. 6 is a similar detail corresponding with Fig. 3. All the figures of the drawings are to one scale.

Our improvements are particularly directed to means for latching down, under pressure, a member, such as pressing arm 2, which may be pivotally supported at its right hand end, Fig. 3, and preferably counterbalanced at that end. Said pivotal mounting and counterbalance are omitted, but are of well known character.

As illustrated in the drawings the mechanism is employed for clamping down under pressure a pile of sheets 3 on stand 4. Another application of our improvements, which we have found particularly useful, is for clamping under pressure, arm or yoke 10 in the hat lining blocking machine set forth in U. S. Letters Patent No. 1,541,997 granted to us June 16, 1925, to which reference may be had. In the device of that patent, to bring pressure to bear on the work in progress, it is necessary to apply considerable force to bring yoke 10 down into position to engage latch 15. This is laborious, particularly when may times repeated, as usual in the constant employment of the machine. To reduce the labor of operation to a minimum is the particular object of the present improvements.

Directing attention now particularly to Figs. 1 and 2 of the drawings the mechanism may be mounted upon table 5, base 6 of the device being secured to said table by some convenient known means not shown. Rising from said base are ears 7, 8 and 9 in which rockshaft 10 has bearings. Fixed to the lefthand end of shaft 10, Fig. 1, is

operating lever 11, which, when in use may be swung from the position of Figs. 1 and 2 in upward direction to the position of Fig. 4. For additional leverage, said lever 11 may be provided with handle 12 extending outwardly to the right therefrom, Fig. 2. For adjustably limiting the movement of said lever in anti-clockwise direction, Fig. 3 for instance, screw 16, threaded in horn 17 of said lever may impinge against base 6, and for adjustably limiting the clockwise movement of said lever, screw 18, similarly impinges against another portion of said base.

Freely pivoted through its hubs 13, 14 on shaft 10 and upstanding therefrom, is latch carrier 15. Projecting to the right therefrom, Figs. 2 and 3, is arm 25 for engagement with post 26 of base 6 for limiting the clockwise movement of said carrier. Also projecting to the right therefrom, Fig. 1, is ear 33 for cooperation with adjustable screw 34 in the free end of arm 35, fixed to the right hand end of shaft 10, for purposes described later herein.

Slidably mounted in said carrier is the latch, indicated in a general way by L. For convenience of adjustment said latch is made up of two members, latch body 19 and latch hook 20. Latch body 19 is free to slide up and down in carrier 15 and is slidably retained therein by cap plate 21, fixed by screws 22 to said carrier. Latch hook 20 lies between ears 23 at the upper end of latch body 19 and is positioned transversely thereby. Bolt 24 is efficient for holding latch hook 20 in adjusted relation with latch body 19. Latch body 19 terminates downwardly in foot 27 the left hand portion, Fig. 3, of which is adapted for engaging cam 30 therebelow and from the right hand portion depends spring bolt 28. Said bolt passes downwardly through suitable openings in base 6 and table 5, to adjustable turnbuckle 29 and thence to spring 31, the lower end of which is secured to bar 32 in fixed relation to table 5.

Between ears 7 and 8 of base 6, cam 30 is fixed to shaft 10. Said cam has its outer face 30^a substantially concentric with shaft 10 and the left corner 30^b is curved downwardly to meet flat side 30^c, see Fig. 6. Also as bolt 28 lies within the path of said cam, the mid-portion of the cam is cut away at 36 to clear said bolt, see Fig. 5.

The operation of our improved latch is as follows: In Figs. 1 and 2 the device is in operative position for holding down, under the tension of spring 31, pressing arm 2 against the stack of sheets 3 on stand 4. At that time cam 30 lies horizontally, as in the detail Fig. 5, and foot 27 of latch body 19 stands just clear thereof, whereby the pull of spring 31 is exerted through said latch body 19 and latch hook 20, directly on arm 2 to compress the material 3 on stand 4.

If now, handle 12 be lifted from the horizontal position of Figs. 1 and 2 to the position of Fig. 3, cam 30 is turned in anti-clockwise direction from the position of Fig. 5 to that of Fig. 6, whereby latch body 19 and hook 20 are raised against the pull of spring 31 and lever 2 is released from engagement with the material on table 4. At this state of the upward movement of handle 12 the point of screw 34 engages ear 33 of carrier 15 and by a further slight anti-clockwise movement of said handle, screw 34 swings carrier 15, latch body 19 and hook 20 to the left and lifts arm 25 free of post 26, and stop screw 16 impinges upon base 6, stopping further movement all as shown in Fig. 4. This last small movement just described swings the latch hook free of pressing arm 2 permitting that arm to rise to the dotted position 2^a, Figs. 3 and 4. If then, handle 12 be released the parts return to the position of Fig. 3 but with arm 2 in position 2^a free of the latch hook. If now, a new pile of sheets 3 having been placed on stand 4, pressing arm 2 is pulled downwardly from position 2^a to the full line position of Fig. 3, latch hook 20 will be crowded slightly to the left as said arm shuts thereover, nearly to the position of Fig. 4. This will cause foot 27 to ride back slightly to the left on cam corner 30^b and as latch hook 20 snaps into place on arm 2, Fig. 3, under the pull of spring 31, foot 27 will take cam 30, lever 11 and handle 12 with it to the right until arm 25 strikes post 26. Cam 30 is then just passing its position of repose relative to foot 27 and the impetus given lever 11 and handle 12 by their movement to the right is sufficient to cause said lever and handle to fall, whereby cam 30 passes to the position of Figs. 1, 2 and 5 and spring 31 is free to exert its pull directly on latch hook 20 to urge pressing arm 2 against stack 3 on stand 4 as in Fig. 2.

Having thus described the construction and operation of our improved automatic pressure latch, what we claim is:

1. In a mechanism of the character described the combination of a base having bearings, a horizontal shaft mounted for oscillation in said bearings, a latch carrier freely mounted on said shaft, a latch mounted for vertical sliding movement in said carrier, a cam fixed to said shaft, a foot

on said latch adapted to be engaged by said cam for raising said latch, a downwardly acting pull spring attached to said latch and means for oscillating said shaft for causing the cam to present its high part to said foot for raising said latch against the pull of said spring.

2. In a mechanism of the character described the combination of a base having bearings, a horizontal shaft mounted for oscillation in said bearings, a latch carrier freely mounted on said shaft, a latch mounted for vertical sliding movement in said carrier, a cam fixed to said shaft, a foot on said latch adapted to be engaged by said cam for raising said latch a downwardly acting pull spring attached to said latch, means for oscillating said shaft for causing the cam to present its high part to said foot for raising said latch against the pull of said spring and means, operatively connected with said shaft oscillating means, for swinging said latch carrier to move said latch into inoperative position.

3. In a mechanism of the character described the combination of a base having bearings, a horizontal shaft mounted for oscillation in said bearings, a latch carrier freely mounted on said shaft, a latch mounted for vertical sliding movement in said carrier, a cam fixed to said shaft, a foot on said latch adapted to be engaged by said cam for raising said latch, a hook on the upper end of said latch, a pressing arm adapted to be engaged by said latch hook, a downwardly acting pull spring attached to said latch, a lever attached to said shaft for rocking said cam, an adjustable stop for limiting the movement of said lever in raised position, means for adjusting the distance of said latch hook from said latch foot and means, operatively connected with said lever, for swinging said latch carrier to disengage said latch hook from said pressing arm, said latch disengaging means being operable succeeding the lifting of the latch by the cam.

4. In a mechanism of the character described the combination of a base having bearings, a horizontal shaft mounted for oscillation in said bearings, a latch carrier freely mounted on said shaft, a latch mounted for vertical sliding movement in said carrier, a cam fixed to said shaft, a foot on said latch adapted to be engaged by said cam for raising said latch, a hook on the upper end of said latch, a pressing arm adapted to be engaged by said latch hook and a downwardly acting pull spring attached to said latch foot remote from the cam-engaging portion of said foot, whereby said spring is efficient for holding said latch in engageable position relatively to said pressing arm.

5. In a mechanism of the character described the combination of a base having bearings, a horizontal shaft mounted for os-

cillation in said bearings, a latch carrier freely mounted on said shaft, a latch mounted for vertical sliding movement in said carrier, a cam fixed to said shaft, a foot on said 5 latch adapted to be engaged by said cam for raising said latch, a hook on the upper end of said latch, a pressing arm adapted to be engaged by said latch hook, a downwardly acting pull spring attached to said latch 10 foot remote from the cam-engaging portion of said foot, a lever attached to said shaft for rocking said cam, an adjustable stop for limiting the movement of said lever in raised 15 position, a stop for limiting the movement of said latch carrier when said latch is in engaging relation with said pressing arm, means for adjusting the distance of said latch hook from said latch foot and means, operatively connected with said lever, for 20 swinging said latch carrier to disengage said latch hook from said pressing arm, said latch disengaging means being operable succeeding the lifting of the latch by the cam.

6. In a mechanism of the character described the combination of a base having bearings, a horizontal shaft mounted for oscillation in said bearings, a latch carrier freely mounted on said shaft, a latch mount-

ed for vertical sliding movement in said carrier, a cam fixed to said shaft, a foot on said latch adapted to be engaged by said cam for raising said latch, a hook on the upper end of said latch, a pressing arm adapted to be engaged by said latch hook, a downwardly acting pull spring attached to said latch foot 35 remote from the cam-engaging portion of said foot, whereby said spring is efficient for holding said latch in engageable position relatively to said pressing arm, a lever attached to said shaft for rocking said cam, an adjustable stop for limiting the movement of said lever in raised position, a stop for limiting the movement of said latch carrier when said latch is in engaging relation with said pressing arm, means for adjusting the distance of said latch hook from said latch foot and means, operatively connected with said lever, for swinging said latch carrier to disengage said latch hook from said 40 pressing arm, said latch disengaging means being operable succeeding the lifting of the latch by the cam.

In witness whereof we hereby affix our signatures this 10 day of June, 1926.
